United States Patent Office.

JAMES DEVERAUX, OF MARSHALL, MICHIGAN.

Letters Patent No. 80,813, dated August 11, 1868.

IMPROVED ROTARY EXCAVATOR.

The Schedule referred to in these Letters Patent and making part of the same.

TO WHOM IT MAY CONCERN:

Be it known that I, JAMES DEVERAUX, of Marshall, in the county of Calhoun, and State of Michigan, have invented certain new and useful Improvements in Rotary Excavators; and that the following is a true and accurate description thereof, reference being had to the accompanying drawings, and to the letters of reference marked thereon, and making part of this specification, in which—

Figure 1 is a perspective view, with the excavator-buckets shown in outline, as when raised for dumping.

Figure 2 is a vertical sectional view of the lower end of the vertical rotating shaft with its attachments.

Similar letters indicate the same parts in each figure.

The nature of this invention consists in constructing an apparatus for the sinking of wells and shafts into the earth, and raising the earth excavated by the same to the surface, and there dumping it with ease and rapidity.

To enable others skilled in the art to construct and use my invention, I will now proceed to describe the same, and name its various parts.

A are standards, supporting the table B, and the lower ends of which rest upon and are firmly secured to the ground. D is a vertical shaft, with a metallic point, C, provided with a proper worm for entering the earth and guiding the apparatus in its descent, its upper part passing through and rotating in a proper opening in the table B, and so arranged that when the excavator has progressed until it has passed down nearly through the table, another shaft may be coupled on and the work continued. 7 is a disk, rotating with the shaft C, and resting upon proper shoulders in the standards A. Under this disk, and secured to the same, are the sheave-blocks E and F. G are horizontal arms, rigidly secured to the vertical shaft D, near its point, and carrying the guide-wheels H, which are adjustable laterally at I, and vertically at J, for the purpose of regulating the "cut" of the excavators M.

The lower section of the vertical shaft D, being square, sliding freely thereon is the metallic frame K, provided with the stirrups L for supporting the excavator-buckets M, which are centrally hinged to the same at N, the excavator-buckets M being secured to their proper relative positions to the frame K by means of the buttons O and pins P. Q are bearing-wheels, keeping the steel edges R of the excavator-buckets M in position to enter the earth. S are dogs, on the horizontal arms J, engaging with and securing the frame K to its proper position, resting upon the said horizontal arms J. The dogs are actuated by the spiral springs T, and are disengaged from the frame K by means of the cords U passing under the pulleys V, and passing up are secured to the ring-bolts in the under side of the disk 7. W are chains, secured to the sides of the excavator-buckets M, and radiating from common central rings, and, by means of the ropes X, secured to these rings, passing through the sheave-blocks E and F to the capstan Y, the dogs being disengaged from the frame K, the excavators are raised to the surface by the ropes X and capstan Y, where they are tipped up and their contents dumped, as shown in red outline, fig. 1. Z is a sweep, attached to the vertical shaft D, to which a horse is attached, rotating the excavator-buckets M, causing them to bore into and fill with earth.

What I claim as my invention, and desire to secure by Letters Patent, is—

An excavator, composed of the standards A, table B, disk 7, sheave-blocks E and F, sweep Z, frame K, buttons O, pins P, stirrups L, hinges N, excavator-buckets M, bearing-wheels Q, chains W, ropes X, the vertical rotating shaft D, metallic point C, horizontal arms G, adjustable guide-wheels H, dogs S, springs T, pulleys V, cord U, and capstan Y, when arranged and operating substantially as described, and for the purposes specified.
